UNITED STATES PATENT OFFICE.

ALFRED DAVIES PRESTON, OF MELBOURNE, VICTORIA, AUSTRALIA.

RAILWAY-RAIL FASTENER.

Application filed October 10, 1927. Serial No. 225,251.

This invention relates to new and useful improvements in railway rail fasteners and more particularly to a tie plate adapted to bear and retain the rail.

5 An important object of this invention is to provide a rail fastener which will retain the rail in fixed position, and is not affected by the lateral or vertical stress of trains.

A further object is to provide a rail fastener, having adjustable clamps to engage and secure the rails and at the same time, be subject to be readily moved to facilitate side-wise alignment of the rails to adjust the gauge of the tracks.

15 A yet further object is to provide a tie-plate with projecting studs adapted to engage the rail clamps in a manner to retain them from lateral movement and at the same time render such clamps pivotal to facilitate engagement with the rails under variable conditions.

A still further object is to provide a tie-plate rail-fastener which will shed water or the like from the spiking means and prevent 25 such liquid from soaking the tie and in such manner render the tie more durable in service.

A still further object is to provide a rail fastener of the character described which 30 is simple to construct, inexpensive to manufacture, efficient and durable in service, positive in action and a general improvement in the art.

Other objects and many of the attendant 35 advantages will be readily appreciated as the invention becomes better understood from a consideration of the illustrative embodiments and for which purpose such descriptive drawings have been provided, wherein

40 Fig. 1 is a plan view of the invention.

Fig. 2 is a section on the plane of line 2-2, Fig. 1 looking in the direction indicated by the arrows.

Fig. 3 is an underside plan view of the 45 rail clamp.

Fig. 4 is a sectional view on the plane of line 4-4 Fig. 3 looking in the direction indicated by the arrows.

Fig. 5 is a plan view of a modified form of 50 the invention.

Fig. 6 is a side elevation of the modified form.

Referring more in detail to the drawings in which similar reference numerals designate 55 corresponding parts throughout the several views.

It will be seen that the fastener comprises a tie plate 6 secured to the tie 7 by the spikes 8 and further spikes 9 in engagement with the clamps 10 which register over the base flange 11 of the rail 12 in a manner to retain the same in fixed relation.

The plate 6 is preferably of elongated, rectangular dimensions and projecting from the upper surface are a plurality of integral, 65 frusto-conical studs 14 through the vertical center of which are threaded orifices 15 adapted to receive either spikes 8 or relatively threaded spikes 9 adapted to anchor the plate. The orifices 16 are produced through 70 the plate 6 at normal and desired points and are adapted to receive further spikes 8 for further anchorage. The frusto-conical studs 14 are provided to retain the clamps 10 from lateral movement and at the same time 75 shed the water or like liquid from the spike, where normally such liquid would tend to soak the tie to the core.

The clamps 10 are preferably of square plan each having produced therein an eccentrically disposed orifice 18 substantially flared to its base margin 19 and so designed to engage over the relative, frusto-conical stud 14 of plate 6 in a manner to pivotally retain the clamp in fixed relation with the 85 plate 6. The upper surface of each clamp 10 is obtusely beveled from the orifice 18 to the margins 17 in a manner to shed all liquid from the orifice, where normally such liquid would tend to soak to the tie. The underside margins 17 are substantially recessed to constitute the lateral marginal flange 20 adapted to register over the base flange 11 of the rail 12.

The spikes 8 are adapted to engage the 95 orifices 16 in a manner to anchor the plate 6 to the tie 7 whilst the threaded spikes 9 are adapted to engage the orifices 18 of clamps 10 and threadedly engage the orifice 15 of plate 6 in a manner to draw said clamp 10 100 into engagement with the base flange 11 of the rail 12 and further engage the tie 7 in a manner to anchor the entire structure.

In the modified form of the invention as illustrated in Figs. 5 and 6 of the drawings, 105 it will be seen that the construction is practically identical, however, provision is made to tilt the rail in a manner to reduce friction and wear of the wheel-flanges and rail-head, which provision comprises the centrally disposed, cross sectional body 21 which is 110 obliquely inclined from the normal plane of

plate 6 in a manner to bear and tilt the rail 12.

In operation and gauge alignment, it will be seen that should the rail 12 require to be moved slightly sidewise, the only operation essential is to loosen spikes 9 which permits the clamps 10 to be disengaged from the rail base 11, align the rail 12 and then rotate the clamps 10 upon studs 14 until the 10 suitable marginal recess 17 registers with the rail base, and the marginal flange 20 engages the rail base 11, then tighten the spikes and the operation is complete.

It will be obvious from the foregoing description, that this invention is a great improvement in railway rail-fasteners and whilst the preferred embodiments have been described yet it is to be understood that minor details in the construction, combination, and arrangement of the cooperating elements may be resorted to within the scope of what is claimed without departing from the spirit of the invention.

What I claim:

- 25 1. A railway rail fastener comprising a plate, said plate adapted to seat the rail and having orifices produced in said plate, said orifices adapted to receive spikes or the like to secure said plate to the tie, a plurality of studs integrally projecting upwardly from said plate, a threaded orifice produced through each of said studs, a plurality of clamps, said clamps adapted to engage over the base flange of the rail, an orifice produced through each of said clamps, said orifice adapted to engage one of said studs, a plurality of threaded spikes adapted to engage a said orifice of one of said studs and fibres of the tie in a manner to draw said clamp into engagement with said stud and over the base flange of the rail.
- 30 2. A railway rail fastener comprising a plate, said plate adapted to seat the rail and having orifices produced in said plate, said orifices adapted to receive spikes or the like to secure said plate to a tie, a plurality of frusto-conical studs integrally projecting upwardly from said plate, a threaded orifice produced through the vertical center of each of said studs, a plurality of clamps, said clamps adapted to engage over the base flange of the rail, an orifice produced through each of said clamps, said orifice sub-

stantially flared to engage one of said frusto-conical studs, a plurality of threaded spikes, each of said threaded spikes adapted to engage a said orifice of one of said clamps and a said threaded orifice of one of said frusto-conical studs and the fibres of the tie in a manner to draw said clamp in engagement with said frusto-conical stud and over the base flange of the rail.

3. A railway rail fastener comprising a plate, said plate adapted to seat the rail, an integral, cross sectional body disposed on the upper surface of said plate, the surface of said body being inclined to the normal plane of said plate surface, orifices produced in said plate, said orifices adapted to receive spikes or the like, to secure said plate to the tie, a plurality of studs integrally projecting upwardly from said plate, a threaded orifice produced through each of said studs, a plurality of clamps, said clamps adapted to engage over the base flange of the rail, an orifice produced through each of said clamps, said orifice adapted to engage one of said studs, a plurality of threaded spikes adapted to engage a said orifice of one of said studs and fibres of the tie in a manner to draw said clamp in engagement with said stud and over the base flange of the rail.

4. A railway rail fastener comprising a plate, said plate adapted to seat the rail, an integral, cross-sectional body disposed on the upper surface of said plate, the surface of said body being inclined to the normal plane of said plate surface and having orifices produced in said plate, said orifices adapted to receive spikes, or the like to secure said plate to tie, a plurality of frusto-conical studs integrally projecting upwardly from said plate, a threaded orifice produced through the vertical center of each of said studs, a plurality of clamps, said clamps adapted to engage over the base flange of the rail, an orifice produced through each of said clamps, said orifice substantially flared to engage one of said frusto-conical studs, a plurality of threaded spikes, each of said threaded spikes adapted to engage a said orifice of one of said clamps and a said threaded orifice of one of said frusto-conical studs and the fibres of the tie in a manner to draw said clamp into engagement with said frusto-conical stud and over the base flange of the rail.

In testimony whereof I affix my signature.

ALFRED DAVIES PRESTON.
